United States Patent

Des. 239,630
Patented Apr. 20, 1976

239,630

ASH TRAY

Edward M. Edwards, Sylvania, and Melvin B. Lee,
Toledo, Ohio, assignors to Owens-Illinois, Inc., Toledo,
Ohio

Filed Sept. 9, 1974, Ser. No. 504,122

Term of patent 14 years

Int. Cl. D27—03

U.S. Cl. D27—27

FIG. 1 is a top plan view of an ash tray showing our new design; and

FIG. 2 is a cross-sectional view taken at line 2—2 of FIG. 1.

We claim:

The ornamental design for an ash tray, as shown and described.
